(57) **CLAIM**

The ornamental design for a portable isolation power supply,
as shown and described.

DESCRIPTION

FIG. 1 is a top front perspective view of a portable isolation power supply showing my new design;

FIG. 2 is a top rear perspective view thereof;

FIG. 3 is a front elevation view thereof;

FIG. 4 is a top plan view thereof;

FIG. 5 is a bottom plan view thereof;

FIG. 6 is a right side elevation view thereof;

FIG. 7 is a left side elevation view thereof; and,

FIG. 8 is a rear elevation view thereof.

The broken lines in the figures depict portions of the portable isolation power supply which form no part of the claimed design.
